INTERNAL COMBUSTION ENGINE

Jacob F. Edgar, Detroit, Mich., assignor to
Packard Motor Car Company, Detroit, Mich.,
a corporation of Michigan

Application April 15, 1931, Serial No. 530,336

4 Claims. (Cl. 123—37)

This invention relates to internal combustion engines and more particularly to compression-ignition engines.

In engines of the type referred to, it is customary to compress air in the cylinders and to inject liquid fuel into the compressed air when the pistons approach top center position during the compression strokes. This manner of operating an engine results in high peak pressures which are 10 undesirable.

An object of my invention is to provide an engine having means associated with the cylinders for relieving peak pressure.

Another object of my invention is to provide 15 an engine in which a portion of the fuel charge is by-passed from the cylinder and again introduced therein when the piston is moving in its working stroke.

A further object of the invention is to provide 20 an engine having a cylinder provided with a conduit opening therein in different axial planes, one end of which is adjacent the head and the other end of which is covered by the piston during its movement adjacent the head, so that a portion of 25 the fuel charge will be trapped from the cylinder and reintroduced when the piston is moved downwardly on its working stroke.

Other objects of the invention will appear from 30 the following description taken in connection with the drawing, which forms a part of this specification, and in which:

Fig. 1 is a vertical sectional view of an engine cylinder, showing my invention associated therewith;

35 Fig. 2 is a sectional view through the cylinder, taken on line 2—2 of Fig. 1.

Referring now to the drawing by characters of reference, 10 indicates an air-cooled engine cylinder having an integral head 11 through which 40 a single port 12 extends for the purpose of admitting air into the cylinder and allowing the escape of exhaust gas.

Within the cylinder there is a reciprocating 45 piston 13 having a rod 14 connected to the crank shaft, not shown, of an engine. The end of the piston is formed with a pocket 15 which registers with a nozzle 16 arranged to extend through the wall of the cylinder adjacent the head. The nozzle illustrated includes a valve head 17 which 50 is arranged to normally close the nozzle but to open inwardly of the cylinder when liquid fuel charges are being injected. It will be understood that the nozzle illustrated is associated with a high pressure pump so that variable liquid fuel 55 charges can be projected well into the cylinder in

an atomized condition such as to readily mix with compressed air charges.

My invention is shown associated with an engine of the four-cycle type in which air is drawn into the cylinder through the valve port 12, is 60 then compressed and a fuel charge introduced therein when the piston is adjacent the head on the compression stroke. Ignition of the fuel charge occurs through compression, whereupon the piston moves in its working stroke, after which 65 the exhaust stroke follows. The port is open during the exhaust and intake strokes of the piston and is closed during the compression and working strokes of the piston.

In engines of this type extremely high peak 70 pressures are produced at the end of the compression strokes. Such peak pressures are very undesirable because of the additional strength required in the cylinder structure and the associated parts, the extreme high heat developed 75 and the inefficiency produced by such a condition.

In order to reduce the peak pressure, I provide 80 by-pass means in which a portion of the fuel charge is trapped, and then admitted to the cylinder during the working stroke of the piston so that no power is lost through its removal. As one means of by-passing a part of the fuel charge, I provide a conduit 18 having its open ends communicating with the interior of the cylinder. 85 One end of the conduit communicates with the interior of the cylinder adjacent the head, while the other end of the conduit is arranged to extend in a plane spaced axially from the end adjacent the head so that it will be closed by the 90 piston during reciprocation adjacent the head.

The end 19 of the conduit extends through the cylinder adjacent the head and is formed with a seat 20 adapted to receive a ball 21 which is normally held seated by a coil spring 22. This 95 ball provides a one-way valve so that the fuel charge forced into the conduit, after the piston has covered the end 23 of the conduit, cannot return through the end 19 and, therefore, will be trapped in the conduit until the piston uncovers the end 23, whereupon the charge will again be introduced into the cylinder and its expansion can take place. In this manner the peak pressure in the cylinder is relieved and the displaced fuel charge is utilized so that there 100 will be no loss of efficiency otherwise caused by its removal.

In order to deflect the trapped fuel charge and to regulate the time at which it is introduced 105 into the cylinder during the working stroke, I 110

provide a projection 24 on the piston end which registers with the opening 23 of the conduit. By forming this deflector of desired length, the time at which the by-passed fuel reenters the cylinder 5 can be accurately timed so that explosion will not take place in the conduit.

While I have herein described in some detail a specific embodiment of my invention, which I 10 deem to be new and advantageous and may specifically claim, I do not desire it to be understood that my invention is limited to the exact details of the construction, as it will be apparent that changes may be made therein without departing 15 from the spirit or scope of my invention.

15. What I claim is:

1. In an internal combustion engine of the compression-ignition type, a cylinder, means for admitting air into the cylinder, means for injecting liquid fuel into the cylinder, a piston in the 20 cylinder, a conduit establishing communication between axially spaced interior portions of the cylinder, one end of the conduit being adjacent the head, and a one-way valve in the end of the conduit adjacent the head, said valve opening 25 toward the remote end of the conduit.

2. In an internal combustion engine of the compression-ignition type, a cylinder, means for admitting air into the cylinder, means for injecting liquid fuel into the cylinder, by-pass 30 means leading from the interior of the cylinder adjacent the head to the interior of the cylinder 35 in a plane axially removed therefrom, a piston

adapted to reciprocate in the cylinder and stopping communication between one end of the by-pass means and the cylinder during its movement adjacent the head, and a deflector projecting from the end of the piston in an axial plane registering with the by-pass end adapted to be closed 80 by the piston.

3. In an internal combustion engine, a cylinder, a piston in the cylinder, means associated with the cylinder to feed fuel therein, exhaust means 85 for the cylinder, conduit means establishing communication between axially spaced interior portions of the cylinder, one end of the conduit means being adjacent the cylinder head, and valve means in the end of the conduit means nearest the cylinder head, said valve means opening 90 toward the remote end of the conduit means.

4. In an internal combustion engine of the compression-ignition type, a cylinder, means for admitting air into the cylinder, means for injecting liquid fuel into the cylinder, by-pass 95 means leading from the interior of the cylinder adjacent the head to the interior of the cylinder in a plane axially removed therefrom, a piston adapted to reciprocate in the cylinder, said piston 100 serving as a valve for one end of the by-pass means during its movement, and means carried by the piston in the path of the by-pass end for directing the movement of the fuel charge escaping from the by-pass end, when uncovered 105 by the piston, toward the head of the cylinder.
